APPARATUS FOR USE WITH
TYPE SLUG SAWS

Frederick I. Hochstadt, Brooklyn, N. Y.

Application January 2, 1936, Serial No. 57,222

5 Claims. (Cl. 29—69)

This invention relates to apparatus for use with cutting and trimming saws employed in printing composing rooms, and has particular reference to an improved apparatus which is selectively operable for directing the sawed lead and wood parts into separate containers and which includes means for visually indicating which of the containers is open for receiving the parts so as to avoid co-mingling of the lead and 10 wood parts in the same container.

The invention comprehends an apparatus including a chute having its open upper end disposed under and in alignment with the saw so as to receive the parts severed by the saw as they drop therefrom, a pair of containers at the bottom of the chute, manually operable means for opening and closing the chute to either of said containers and an indicating device operatively connected to and movable with said means for visually indicating which of said containers is open.

The invention further includes in an apparatus of the character described, a switch interposed in the circuit with the driving motor of the saw, which switch is actuated by movement of the chute opening and closing means for breaking the motor circuit when the said means is in open relation with both of said containers and for closing the motor circuit when the said means is moved to fully closed position with either one of said containers.

With the foregoing and other objects in view, reference is now made to the accompanying drawing in which there is illustrated the preferred embodiments of the invention, while the appended claims cover variations and modifications thereof which fall within the scope of the invention.

In the drawing:

Fig. 1 is a perspective view of a type slug saw in association with an apparatus embodying the invention.

Fig. 2 is a vertical longitudinal sectional view taken approximately on line 2—2 of Fig. 3.

Fig. 3 is a vertical transverse sectional view taken approximately on line 3—3 of Fig. 2.

Fig. 4 is an enlarged plan view of the switch mechanism.

Fig. 5 is a front view of a modified form of the apparatus.

Fig. 6 is a horizontal sectional view taken approximately on line 6—6 of Fig. 5.

Referring to Figures 1 to 4 inclusive of the drawing, by characters of reference, 10 designates a rotary disk saw of the character em-

ployed in printing composing rooms for cutting up lead slugs, metal type or other metal material and wooden reglets, spacers, wood cuts and electrotype, etc., and which includes a driving motor 11 operatively connected to the saw by means of a belt 12 which operates over pulleys 13 and 14 carried by the shafts of the motor and saw respectively, a base 15 which supports the saw and provides a platform on which the material is fed thereto and a cabinet 16 on which the base 15 is mounted and which houses the motor 11.

For the purpose of providing means for collecting the severed lead and wood parts in separate containers, the cabinet 16 is provided with a downwardly directed chute 17 having an open upper end disposed under the saw and in alignment with the opening 18 in the base 15 through which opening the severed parts drop as they leave the saw. The chute 17 is preferably of rectangular shape in cross sectional configuration and is provided at the bottom thereof with a part of containers or drawers 19 and 20 which are open at the top and in communication with the chute. The said containers or drawers are arranged in side by side relation at the bottom of the cabinet 16 and are slideable in an opening 21 preferably in the front panel of the cabinet 16 so that the same may be withdrawn for emptying the sawed parts. The chute 17 is provided with a vertical partition 22 extending longitudinally of the containers 19 and 20 and from the upper inner edges thereof to terminate in spaced relation with the upper open end of the chute and which subdivides the chute into laterally arranged ducts 23 and 24 which open at their lower ends into the containers 19 and 20 respectively.

A deflector flap 25 is arranged within the chute above the partition 22 with its lower longitudinal edge disposed in longitudinal alignment with the upper edge of the partition and secured to a rock shaft 26 pivoted in bearing openings 27 and 28 in the front and rear walls respectively of the chute. The rock shaft 26 extends forwardly through a bearing opening 29 in the front wall of the cabinet and is provided with a hand knob 30 on its free forward end for manually rocking the shaft so as to selectively dispose the deflector flap in downwardly sloping, inwardly directed covering relation with the upper ends of the ducts 23 and 24 respectively so that when the same is in covering relation with either one of the ducts the parts severed by the saw will be de-

flected into the open duct as the same drop thereupon.

An indicator 32 is arranged at the rear of the cabinet in the line of vision of an operator in front of the saw and is provided with indicia such as the word "wood" on one side thereof, and the word "metal" on the opposite side thereof, for visually indicating which of said containers 19 and 20 is in open relation with the chute. The indicator 32 is carried by the upper end of a rotary shaft 33 which is journaled in bearings 34 carried by the base and the rear wall of the cabinet respectively. The shaft 33 is operatively connected with the rear end of the rock shaft 26 by intermeshing miter gears 35 and 36 for imparting movement to the indicator 32 in timed relation with the movement of the deflector flap 25. In order to prevent operation of the saw when the deflector flap 25 is in any intermediate position where both of the ducts 23 and 24 are open and to permit of the operation of the saw only when one of the ducts is fully closed by the deflector flap 25, a circuit maker and breaker 37 is arranged in the motor circuit 25 38. The circuit maker and breaker 37 includes a stationary contact member 39 having spaced contact points 40 and 41 and a movable contact arm 42 attached to the rotary shaft 33 and extending radially therefrom for movement therewith to respectively engage with the contact points 40 and 41 when the deflector flap 25 is in either of its two fully closed positions with relation to the ducts 23 and 24.

In the modified form of the invention illustrated in Figures 5 and 6 of the drawing, the deflector flap 45 is secured to a shaft 46 pivoted in bearing openings in the front and rear walls of the chute 47 adjacent the upper inner edges of the containers 48 and 49 and extends upwardly therefrom to a point where it terminates at the upper end of the chute. In this form, a manipulating rod 50 is connected with the deflector flap 45 adjacent its upper end and extends through aligned arcuate slots 51 and 52 in opposite walls of the chute 47 and through corresponding aligned slots 53 and 54 in opposite walls of the cabinet 55, the forward end of the rod 50 protruding from the cabinet and being provided with a manipulating knob 56. The rear end of the rod 50 protrudes from the cabinet 55 and is connected by a cable 57 to the periphery of the indicator shaft 58 so that as the deflector flap 45 is swung from one position to the other, the indicator shaft 58 is turned a half revolution to selectively display the indicia on the indicator 59 in accordance with the relative position of the deflector flap. In this form of the invention, the motor circuit 60 is opened and closed by means of a switch contact 61 on the manipulating rod 50 which selectively engages the fixed contacts 62 and 63 supported so as to be engaged by the contact 61 when the deflector flap is in either of its two fully closed relations to the containers 48 and 49.

65 What is claimed is:

1. In an apparatus of the class described in combination with a driven saw, a support therefor, a chute within said support having an open upper end disposed under said saw, a pair of containers located at the bottom of the chute, manually operable means disposed within the chute above the containers for selectively open-

ing and closing the chute to said containers, and an indicating device located at the rear of the saw, extending above the said support and operatively connected with said means to move therewith for visually indicating which of said containers is in open relation with said chute. 5

2. In an apparatus of the class described in combination with a driven saw, a support therefor, a chute within said support having an open upper end disposed under said saw, a pair of containers located at the bottom of the chute, a manually swingable deflector flap disposed within the chute above the containers for selectively opening and closing the chute to said containers, and an indicating device located at the rear of the saw and in the line of vision of an operator in front of the saw and operatively connected with said deflector flap to move therewith for visually indicating which of said containers is in open relation with said chute. 10 15

3. In an apparatus of the class described in combination with a motor driven saw, a support therefor, a chute within said support having an open upper end disposed under said saw, a pair of containers located at the bottom of the chute, 25 manually operable means disposed within the chute above the containers for selectively opening and closing the chute to said containers, an indicating device operatively connected with said means to move therewith for visually indicating 30 which of said containers is in open relation with said chute, and a switch interposed in the motor circuit and operatively connected to said means for movement therewith to break the motor circuit when the said means is in open relation with both of said containers and for closing the motor circuit when the said means is in fully closed relation with either one of said containers.

4. In an apparatus of the class described in combination with a motor driven saw, a support 40 therefor, a chute within said support having an open upper end disposed under said saw, a pair of containers located at the bottom of the chute, a manually swingable deflector flap disposed within the chute above the containers for selectively opening and closing the chute to said containers, an indicating device located at the rear of the saw and in the line of vision of an operator in front of the saw and operatively connected with said deflector flap to move therewith for visually indicating which of said containers is in open relation with said chute, and a switch interposed in the motor circuit and operatively connected to said means for movement therewith to break the motor circuit when the said means is in open relation with both of said containers and for closing the motor circuit when the said means is in fully closed relation with either one of said containers. 45 50 55

5. In an apparatus of the class described in combination with a driven saw, a support therefor, a chute within said support having an open upper end disposed under said saw, a pair of open top containers housed within said support and located at the bottom of the chute in communication therewith, and manually operable means disposed within the chute above the containers for selectively opening and closing the chute to said containers, said containers being slidably removable through an opening in said support 70 for emptying the same. 60 65 70
